UNITED STATES PATENT OFFICE

HOWARD G. ALLEN, OF NIAGARA FALLS, NEW YORK, ASSIGNOR TO H. R. BLISS COMPANY, INC., OF NIAGARA FALLS, NEW YORK, A CORPORATION OF NEW YORK

STITCHER HEAD

Application filed March 9, 1928. Serial No. 260,287.

This invention relates to a stitcher head of a type for placing wire securing stitches in fibre board containers and the like.

The invention has as an aim the provision of a stitcher head capable of operating at a rate of speed higher than stitcher heads heretofore proposed. One of the difficult problems which is met with in operating a stitcher head at high speeds, is what is known as overrun of the wire feed. Stitcher heads include a mechanism for feeding wire from a continuous length which is cut off and formed into a stitch, and when operating at high speeds this mechanism tends to overrun, due to the speed, and too much wire is fed. Moreover, this overrunning action may not be continuous but may occur from time to time, thus jamming up the stitcher head and preventing operation. Accordingly, the invention contemplates a feed mechanism which feeds a length of wire which is to form a stitch at varying speeds; that is to say, at a given operating speed of a stitcher head, the speed at which the wire is fed varies. This variation is such as to reduce feeding speed near the end of the feeding operation so that the wire which is fed comes rather gradually to a stop, so as to prevent an overrun.

Other objects of the invention include a more simplified construction, and a construction wherein some of the members which are subjected to considerable wear are detachably connected to other associated members so that they can be readily replaced from time to time, also a new and improved stitch supporting mechanism which is more compact and rugged than heretofore has been the case.

In the accompanying drawings:

Fig. 1 is a perspective view of a stitcher head with parts cut away and parts in section showing, in general, the construction of the stitcher head.

Fig. 2 is a sectional view showing particularly, the wire feed mechanism.

Fig. 3 is a view taken on line 3—3 of Fig. 2 showing a construction of a former slide and drive bar.

Fig. 4 is a view taken on line 4—4 of Fig. 2 showing the mechanism for severing the wire.

Figs. 5 and 6 are detailed rear views of a

stitcher head showing the operating mechanism for the drive bar and the wire cutting mechanism operated by the drive bar actuating mechanism.

Fig. 7 is a detailed view looking into the front of the stitcher head mechanism showing the parts of the wire feed mechanism in position just prior to an operation.

Fig. 8 is a view similar to that of Fig. 7 but showing these parts just after the drive bar begins its downward movement. Fig. 9 shows the drive bar and connections with the wire feed, with the drive bar approaching its lowermost position.

Figs. 10 and 11 are detail views showing a length of wire formed into a staple, and illustrating the manner in which the staple is driven outwardly by the driver.

Fig. 12 is a detail view in perspective showing the stitch gripper mechanism.

Fig. 13 is a detail in perspective of the shoe or supporting device for the legs of a wire stitch showing the mounting and operating mechanism therefor.

The stitcher head consists of a main body portion 1 which is adapted to be secured to the structure, a stitching machine (not shown). This stitcher head includes the usual former and driving mechanism, the former slide being referenced 2 and the drive bar referenced 3, as best shown in Figs. 3, 7 and 8. As a means for reciprocating the former slide, the same is provided with a stud 4 which is received in a cam groove with an interposed antifriction roller. As a means for reciprocating the drive bar, the same is provided with a stud 5 (Fig. 3) which projects through a slot 6 in the former slide, and on this stud is mounted a crank 7 having a stud 8 adapted to be received in a hole in a rotating member, preferably the cam which actuates the former slide.

Thus far, the mechanism is much the same as the heretofore proposed stitcher heads, and these parts operate as shown in Fig. 10 with the former slide 2 moving downwardly prior to the drive bar and shaping a length of wire, as shown at 9 (Fig. 8) into a staple form (Fig. 10) and then the drive bar comes down and ejects the staple as shown in Fig. 11. A

suitable anvil (not shown) is positioned below the stitcher head to clench the legs of the staple, and the article to be stitched is placed so that the legs of the staple are driven therethrough in the usual manner.

5 A driver which actually engages the stitch and drives the same through the material to be stitched is connected to the drive bar 3 to permit ease of assembly and disassembly 10 and replacement of the part when necessary, and this driver is shown at 10. This driver slides between the two parts of the former slide and, as shown in Fig. 3, it is connected to the drive bar 3 by means of an interengaging 15 projection and recess, the projection 11 being on the drive bar which engages in the recess in the driver. It will thus be seen that the driver 10 may be quickly assembled or disassembled and is easily replaceable.

20 Wire for the stitches is fed through a guide or tube 15 and between drive rollers 16 and 17 which are geared together, and thence through a tube or guide 14. The drive roller 17 is keyed to a shaft 18, also keyed to this 25 shaft is a gear toothed clutch wheel 19 constructed to drive the shaft when power is applied to the wheel in one direction, and to slip when power is applied in another direction so that the two drive rollers are driven in one 30 direction with step by step movement. The particular arrangement of this clutch wheel is not of particular importance, but it is depicted generally in Fig. 1.

35 A housing 20, which is shown in Fig. 1 but which is cut away in this figure, fits onto the front of the head and is arranged to pivot on the shaft 18. This housing is provided with an arcuate slot 21 through which extends a clamp screw 22 so that the housing is rotatably adjustable around the stud 18 and can be set in any position by tightening the clamp screw. This housing carries a stud 25 (Fig. 40) which pivotally carries a gear toothed segment 26 which meshes with the teeth in the 45 gear wheel 19, thus to drive the driving rolls for the wire.

The segment has an arm 27 which pivotally carries a fork or yoke 28 (Fig. 1). This yoke slidably fits over an arm 30 which is pivoted 50 to the stitcher head at 31 (Fig. 2). The opposite end of this arm 30 is pivotally connected to a link 32 which is in turn pivoted to the drive bar at 33. This construction drives the wire feed and its action is important, especially 55 in the operation of high speeds.

The reciprocation of the drive bar 3 acts through the construction just described to rock the segment. As shown in Fig. 7, the drive bar is in its approximate uppermost position; Fig. 8 represents a drive bar after it has moved downwardly somewhat, and Fig. 9 represents the parts when the drive bar is in lowermost position. It is to be noted that the point 33 on the drive bar moves away 65 from the pivotal point 31 as it approaches its

lowermost position. This causes the link 32 to swing. Accordingly, on the first movement of the drive bar the adjacent end of the arm 30 moves with it at about the same speed, but as the drive bar goes downward the link 70 32 swings upwardly, so that the downward speed of the lower end of the link and the adjacent end of the arm 30 is diminished with respect to the movement of the drive bar. Thus, the movement of the segment and the 75 driving rolls diminish in speed as they approach the end of the feed movement, and they are stopped at the end of the feed movement gradually with relation to the relatively abrupt stop of the drive bar. Accordingly, the wire is fed with diminishing speed, 80 and overrun is thus avoided. This avoidance of the overrun of the wire feed permits the operation of the stitcher head at an increased speed.

85 As heretofore mentioned, the housing 20 which pivotally carries the segment 26, pivots at 18. By reference to Fig. 1 it will be noted that by loosening the clamp screw 22 the housing can be pivoted, and this slides the 90 yoke 28 along the arm 30 and accordingly varies the stroke of the segment and the length of the wire feed. The further the yoke is from the pivotal point 31 the greater the stroke, and the greater the amount of wire 95 fed at each stroke, and vice versa. This permits adjustment of the wire feed and suitable indicia may be provided for adjusting the housing, as shown in Fig. 1.

100 The wire is fed from the tube 14 into a cutter tube 35. This cutter tube or hollow die is held by set screws 36 in a unitary and removable unit 37 or cutting block, grooved as at 38 for receiving an inwardly extending piece 39 on the stitcher head, and being held in place by a screw 40 extending through an elongated slot 41 (Figs. 1 and 4). This entire unit can be removed by removal of the screw 40 and then swinging the same outwardly from the bottom to disengage the 105 groove and projections 38 and 39. This unit also includes a knife 42 carried by a member 43 normally spring pressed upwardly. In each cycle of operation the knife is moved downwardly to cut the wire. A simple 110 mechanism is provided for depressing the member 43 to actuate the knife. This mechanism takes the form of a rock shaft 45 (Fig. 4) which carries an arm 46. This shaft is cut away as at 47 to engage a plunger 48. In each cycle of movement the crank 7 which actuates the drive bar contacts with the arm 46 in a manner shown in Fig. 6 and rocks the shaft 45 to depress the plunger, which in turn depresses the member 43 and 115 knife. The entire cutting block mechanism and knife are removable as a unit and can be detached and assembled at any time without interference whatever with the operable connection in the actuating mechanism, inas-

120 125 130

much as the block just moves out from underneath the plunger 48.

This cutter block is movable transversely of the stitcher head to accommodate for different lengths of wire to be fed in order that the legs of the staple shall be of equal length. For this purpose a slide 50 is provided (Fig. 1) and shaped as at 51 for receiving a projection 53 on the housing 20. The block 37 has a screw 54, the head of which is received in a slot in the slide 50. This screw is adjustable and may be locked by a set screw 55. Upon rotational adjusting movement of the housing around the pivot point 18 the slide 50 is moved in and out, and accordingly the block 37 moves. Fine adjustment to exactly center the cut piece of wire in the gripping mechanism is obtained by adjusting the screw 54. When the block 37 is removed the head of the screw 54 merely moves out of the slot in the slide.

The wire is fed as the stitching operation is being performed, with the drive bar and the former slide moving downwardly. As shown in Fig. 3 the wire being fed out through the cutter block is disposed to one side of the drive bar and the wire is received by a gripper 60. A cam block 61 (Fig. 1) is on the former slide and engages a stud 62 on the gripper. This stud is screw threaded into a split block 63 which may be tightened by a screw 64, whereby to permit adjustment of the camming action. As the former slide comes down the cam 61 pushes the gripper into alignment with the wire feed as shown in Fig. 3, the gripper being pressed normally against the camming action by springs 65. The gripper in the main is pivoted as at 66 and it includes a second slideable member 67 (Fig. 12) with a stud 68 which engages in an opening 69 in a slide 68'. This slideable member is urged into stitch gripping position, as shown in Fig. 12 by a spring 67'. The slide 68' has a pair of notches 68^a and 68^b which cooperate with a spring pressed plunger 68^c. As the gripper comes down the link 7 strikes the top of the slide and knocks it down; before being knocked down it was held up by the spring pressed plunger 68^c in the notch 68^a; after being knocked down it is held by the plunger and notch 68^b. It then grips the length of wire which is to be severed and formed into a stitch.

In the upward movement of the stitch forming mechanism the gripper places the separate piece of wire in proper position, whereupon the slide member 67 is moved up again to release this wire. This is accomplished by the driver 10 striking the lower end of the member 68'. By noting Fig. 3 it will be observed that the driver 10 projects outwardly somewhat from the drive bar 3 and the member 68' is in its path.

This wire gripper is of a novel construc-

tion in that it eliminates the threading of the wire through a plurality of relatively small places. Noting Fig. 12 it will be observed that the removable member 67 has a foot or gripping piece 67^a and that a cooperating relatively stationary member has slotted guide devices 66^a. The wire is gripped by these two parts. Thus at the side 66^b there is no slot through which the wire may be fed. It has been the practice to reciprocate the movable member corresponding to the one 67 between two separated wire gripping members similar to the one 66^a, thus utilizing these gripping devices, but in the present construction there are only two of such gripping devices disposed side by side.

For the purpose of supporting the staple legs as the staple is being driven, there is a housing 70 carried on the former slide which houses a curved guide member 71 (Figs. 3, 5, 7 and 13) acted upon by springs 72 through a cross head 73. Levers 74 connect with the cross head and have rollers 75 which operate in guideways 76. The springs normally urge the member 71 so that its lower end moves in between the two parts of the former guide (Fig. 10). When the former guide is in uppermost position the rollers strike the projections 77 and the levers are swung to retract the member 71. When the former guide approaches lowermost position the rollers strike the bottom portion of the guide (Fig. 6) and swing the levers to cause this member to project outwardly between the portions of the former slide and support the legs of the stitch, as it is driven through a resisting medium. The upper surface of this member is of cam-like formation and it is pushed out of the way as the driver comes down to drive the stitch. The housing 70 is provided with a slotted portion 80, and the guide member 71 is fixed to a pin 81 projecting through this slot and slidably received in the cross head 73, as shown at 82, Fig. 13. The levers 74 have fulcrum devices 83 which are carried in elongated openings 84 in the housing. It will be seen therefore, that by rocking the levers 74 on the fulcrum members that the cross head 73 is raised or lowered and due to its slideable connection with the pin 81 reciprocates the curved guide device.

The rocking of the levers 74, as above pointed out, is effected by the rollers 75 being engaged in slots 76 and as the former slide raises and lowers these levers alternately strike the bottom and top ends of these guides. An advantage of this construction is the long life assured of the springs 72. The position in which the stitcher head is ordinarily left idle the parts are in approximately the position shown in Fig. 13 with the fulcrum members 83 resting in the bottom of the elongated slots 84. Thus the springs 72 are not under substantial tension but are in practically their normal position. Thus

when the stitcher is left idle over a period of time the springs are not left under tension. These springs instead of being connected on or adjacent the ends of the rocking levers, 5 where they would be subjected to considerable tension, are connected in substantial alignment with the fulcrum point which is movable in the elongated slots and the springs tend to hold the fulcrum members 10 in the bottom of the slots.

It will be seen that the stitcher head affords a novel form of driving mechanism for the wire feed which effects a slowing down of the feeding motion as it approaches its stopping 15 point. Thus, the feed of the wire is not stopped abruptly, and accordingly overrun is prevented. Moreover, the construction affords a simple adjustment for the length of the wire feed, and which can easily be made 20 by merely shifting the position of the housing rotatably on the stitcher head. Simultaneously with this adjustment the cutter block unit is moved by its connection with the housing. This entire cutter block is a 25 unit in itself and detachable from the stitcher head, as above described, and when detached this unit for replacement of the cutter block or knife or what not, no connection need to be interfered with, as it merely moves out 30 from under the operating plunger. Moreover, the manner in which the driver is connected to the drive bar is a simple and efficient one and permits ready replacement of the driver.

35. Claims:

1. In a stitcher head, the combination of a stitch forming and driving mechanism including a reciprocating drive-bar, means for feeding wire to said mechanism, and an operable connection between the drive bar and the feeding means arranged to utilize the reciprocating movement of the drive bar to intermittently operate the feeding means, said connection consisting of relatively movable members which operate to drive the wire feeding means at speeds which vary with respect to the rate of speed of the movement of the drive bar, with the rate of speed of the feeding means diminishing near the end 50 of each intermittent feeding movement.

2. In a stitcher head, the combination of a stitch forming mechanism including a reciprocating member, means for feeding wire to said mechanism, and an operable connection between the said reciprocating member and the feeding means arranged to utilize the reciprocating movement of the member to intermittently operate the feeding means, said connection consisting of relatively movable members which operate to drive the wire feeding means at speeds which vary with respect to the rate of speed of the movement of the said member, with the rate of speed of the feeding means diminishing near the end 55 of each intermittent feeding movement.

3. In a stitcher head, the combination of a stitch forming mechanism including a reciprocating member, wire feeding means, a link pivoted to the reciprocating member, an arm pivoted at one end of the link and having a fixed pivot at its other end, and means associated with this arm for driving the feeding means, whereby movement of the reciprocating member intermittently actuates the feeding means, said link and arm being adapted to pivot with respect to each other whereby to vary the speed of the wire feed with respect to the speed of the reciprocating member.

4. In a stitcher head, the combination of a stitch forming and driving mechanism including a reciprocating stitch forming member and an associated reciprocating stitch driving member, wire feeding means, a one-direction gear for driving the wire feeding means, a pivoted segment engaging the gear, an arm operably associated with the segment, one end of which is mounted on a fixed pivot, a link pivoted to the other end of the arm, and a pivoted connection between the reciprocating stitch driving member and the link, whereby reciprocating movements of the stitch driving member intermittently actuate the wire feeding means.

5. In a stitcher head, the combination of a reciprocating stitch driving member, wire feeding means, an arm operably associated with the wire feeding means, a fixed pivot at one end of the arm, a link, a pivotal connection between the link and the reciprocating member, and a pivotal connection between the arm and the link, the parts being arranged so that the distance between the fixed pivot of the arm and the pivotal connection between the link and the reciprocating member varies as this drive member moves, whereby the link and arm pivot to accommodate for this varied distance, thus to diminish the speed of movement of the arm and the speed of movement of the wire feeding mechanism.

6. In a stitcher head, the combination of a stitch supporting shoe for supporting the legs of a stitch while being driven through material to be stitched, a housing in which the shoe is mounted for movement, levers fulcrumed on the housing, a cross head connecting the levers, means connecting the shoe to the cross head, springs acting on the levers and connected thereto near the fulcrum points, whereby the tension of the springs is minimized, and means for actuating the levers.

7. In a stitcher head, the combination of a shoe for supporting the legs of a stitch while being driven through material to be stitched, a housing in which the shoe is mounted for movement, a pair of levers, means for actuating the levers, said levers being loosely fulcrumed, a cross head con-

necting the levers, a connection between the cross head and the shoe, and springs connected respectively to the housing and the levers adjacent the fulcrum points of the levers whereby the tension of the springs is minimized upon the actuation of the levers.

8. In a stitcher head, the combination of a shoe for supporting the legs of a stitch while being driven through material to be stitched, a housing in which the shoe is mounted for movement, a pair of levers, means for actuating the levers, the said levers being fulcrumed in elongated openings in the housing, a cross head connecting the levers, a connection between the cross head and the shoe, and springs connected respectively to the housing and the levers adjacent the fulcrum points of the levers, whereby the tension of the springs is minimized upon the actuation of the levers.
10. 9. In a stitcher head, the combination of a shoe for supporting the legs of a stitch when being driven through material to be stitched, a housing in which the shoe is mounted for movement, said housing being provided with elongated openings, a pair of levers fulcrumed in these elongated openings, means for rocking the levers, springs connected to the levers adjacent their fulcrum points and also connected to the housing, a cross head connecting the levers, and a pin secured to the shoe and having a slidable connection with the said cross head.

10. In a stitcher head, the combination of a shoe for supporting the legs of a stitch when being driven through material to be stitched, a housing in which the shoe is mounted for movement, said housing being provided with elongated openings, a pair of levers fulcrumed in these elongated openings, means for rocking the levers, springs connected to the levers adjacent their fulcrum points and also connected to the housing, a cross head connecting the levers, and a pin secured to the shoe and having a slidable connection with the said cross head, said housing being provided with a slotted portion through which the said pin extends.

11. In a stitcher head the combination of a reciprocating member in the stitching mechanism, a shoe for supporting the legs of a stitch, a housing in which the shoe is mounted for movement, said housing being mounted on the said reciprocating member, a pair of levers fulcrumed to the housing, means on the stitcher head for rocking the levers on the fulcrum points, springs acting on the levers and connected thereto adjacent the fulcrum points of the levers, a cross head connecting the levers, and a slidable connection between the shoe and the cross head.

12. In a stitcher head the combination of a reciprocating member in the stitching mechanism, a shoe for supporting the legs of a stitch, a housing in which the shoe is mounted for movement, said housing being mounted

on the said reciprocating member, a pair of levers fulcrumed on the housing, means on the stitcher head for rocking the levers on the fulcrum points, springs acting on the levers and connected thereto adjacent the ful-

70 crum point of the levers, a cross head connecting the levers, and a slidable connection between the shoe and the cross head, the said means on the stitcher head for rocking the levers consisting of closed end guideways in which the ends of the levers operate, whereby the levers are rocked as the said reciprocating member and housing reciprocate.

75 13. In a stitcher head the combination of a reciprocating member in the stitching mechanism, a shoe for supporting the legs of a stitch, a housing in which the shoe is mounted for movement, said housing being mounted on the said reciprocating member, a pair of levers fulcrumed on the housing, means on the stitcher head for rocking the levers on the fulcrum points, springs acting on the levers and connected thereto adjacent the fulcrum point of the levers, a cross head connecting the levers, and a slidable connection 80 between the shoe and the cross head, the said levers being fulcrumed by means of fulcrum members carried in elongated slots in the housing whereby the normal position of the fulcrum members lie adjacent one end of the 85 elongated slots so that the springs are not under substantial tension.

90 14. In a stitcher head, a gripper device for gripping a length of wire to be formed into a stitch, comprising a member having a foot portion for receiving the wire stitch, and a second member movable relative to the first and positioned alongside of the first and above the foot whereby said wire stitch may be gripped by the two members disposed side 95 by side.

100 15. In a stitcher head, a gripper device for gripping a length of wire to be formed into a stitch, comprising two cooperating gripping members, one of which is movable relative to the other to effect gripping and releasing of the wire, one of said members having a single slotted portion and a foot portion for receiving the wire stitch and the other said member having a part disposed at one side 105 of the slotted portion and above the foot and arranged to move into wire gripping position whereby the wire is gripped solely by the two side by side parts.

110 16. In a stitcher head, a gripper device for gripping a length of wire to be formed into a stitch, comprising a primary gripping member including a single part which is slotted for receiving a wire, and a second part movable relative to the first and disposed alongside of the said slotted part of the primary member and arranged to move to and from wire gripping position, said first mentioned part having a portion lying under the second mentioned part, whereby the wire stitch is 115 120 125 130

gripped solely by the slotted part and the movable part.

17. In a stitcher head, a gripper device for gripping a length of wire to be formed into a stitch, comprising a primary gripping member including a single part which is slotted for receiving a wire, a second part movable relative to the first and disposed alongside of the said slotted part of the primary member and arranged to move to and from wire gripping position, whereby the wire stitch is gripped solely by the slotted part and the movable part, and an unobstructed surface on the primary member positioned on the side of the movable member opposite that of the slotted part.

18. In a stitching machine, or the like, the combination of a stitch forming and driving mechanism, means for advancing wire to said mechanism, driving means for intermittently actuating the advancing means, and means for connecting the driving means and wire advancing means, said connecting means being arranged to progressively diminish the speed of movement of the wire advancing means relatively to the speed of movement of the driving means substantially throughout the entire range of intermittent movement.

19. In a stitching machine, or the like, the combination of a stitch forming and driving mechanism, means for advancing wire to said mechanism, a reciprocating driving member, and means connecting the driving member and the advancing means so that the advancing means is intermittently operated during a reciprocable stroke of the driving member, said connecting means being arranged to progressively diminish the speed of movement of the wire advancing means relatively to the speed movement of the driving member during the said reciprocable movement substantially throughout the entire reciprocable movement.

45 In testimony whereof I affix my signature.
HOWARD G. ALLEN.
